ENCLOSURE DEVICE

William J. Condon, Philadelphia, Pa.

Application January 11, 1936, Serial No. 58,738

8 Claims. (Cl. 20—1.6)

The object of this invention is to provide a novel and highly practical form of removable or retractable enclosure for the entrance area of a store or other building.

The invention has a specific application to stores of the chain variety wherein it is customary to deliver goods, including the perishable commodities, in which the store deals, from the central depots or sources at periods, such as in the early morning, outside of the regular hours at which the store is open for business. It has been found impracticable to provide the delivery truck drivers with access to the interior of the stores, and it is customary for the delivery men to deposit the supplies on the exterior of the building where they are exposed to depredations and petty thievery. There is in this system no possibility for adequate check-up on delivered goods, and the losses to the stores are heavy, running into thousands of dollars annually.

The object of the present invention, therefore, is to provide an enclosure device which may be adjusted to and from a position in the interior of the building surrounding the door area, so that the delivery men may be provided with keys for admission to the interior of the building without, however, giving them access to the body of the store. For practical purposes, an inner enclosure of this type must be of a character that will permit ready adjustment to the operative position and equally ready retraction into a non-obstructing position so that during the regular hours normal access is afforded to the store. It is also necessary to provide means for securely locking the enclosure device in the operative position. My invention contemplates the provision of an improved enclosure device of this character which shall meet all the operating requirements, and which may be constructed and installed at reasonably low expense.

In the attached drawings:

Figure 1 is an elevational view of an enclosure device made in accordance with my invention, the enclosure being shown in its operative position;

Fig. 2 is a section on the line 2—2, Fig. 1; Figs. 3 and 4 are fragmentary elevational views illustrating a detail of the construction;

Fig. 5 is a fragmentary sectional view illustrating a desirable form of locking means, and

Fig. 6 is a diagram showing the electric control system.

With reference to the drawings, 1 is a platform supported by suitable brackets 2, 2 and suspension elements 3, 3 above the entrance door 4 and in the interior of the building, the suspension ele-

ments 3 being suitably secured at their upper ends to the ceiling, which is indicated at 5. The platform 1 supports an electric motor 6, which is connected through suitable gearing 7 to a shaft 8 journaled in bearings 9 also mounted on the platform 1. The shaft 8 comprises two sections united by a suitable friction clutch 11, one section of this shaft carrying an element of the gearing 7, and the other carrying a worm 12. This worm is operatively associated with a worm wheel 13 on a shaft 14 extending at right angles to the shaft 8, see Fig. 2, this shaft being journaled in suitable bearings 15, 15 on the platform 1 and having secured thereto a plurality of winding drums 16, which in the present instance are four in number.

Suspended from the ceiling 5 in a position above each of the drums 16 is a pulley 17 which functions to guide a plurality of cables 18 to the respective drums. The cables 18 extend respectively toward and beyond the four corners of the platform 1 and downwardly over pulleys 19 which are suspended from the ceiling 5 at points beyond the edges of the platform. The cables 18 pass downwardly from the pulleys 19 through apertures or recesses in a series of bars 21 and are attached at their lower ends to the lowest bar 22 of the series. The bars 21 and 22 are in the present instance of U-shape, as shown clearly in Fig. 2, and are arranged in assembly 20 to embrace the door area. In the operative position of these bars, as illustrated in Fig. 1, the top bar 21 of the series is suspended by three sets of links 23—24 connecting respectively to the front and sides of the bar from the upper ends of three brackets 25 mounted on and extending upwardly from the platform 1. The links 23 and 24 of each set are respectively pivotally connected to the said top bar 21 and to the associated bracket 25, and are pivotally joined together at their adjacent ends so that when the bar 21 is elevated, the links will fold about their pivotal connection toward each other. Each of the other bars 21 and the bar 22 is connected to the next higher bar of the series by similar though smaller sets of links 26—27. The arrangement is such that when the bars are in their lowered or operative position, as shown in Fig. 1, the bar 22 rests upon or lies adjacent to the floor surface 28. As shown in Figs. 2 to 5, the bars 21 and 22 in the present instance are cross-sectionally of angle formation.

The construction and mode of operation of the links 26—27 is illustrated in Figs. 3 and 4. Each of the links 26 is pivotally connected at 29 to a hinge bracket 31 suitably secured to the under

side of the upper one of the two connected bars. The link 27 is similarly pivotally connected at 32 to a corresponding hinge bracket 33 secured to the lower of the two connected bars. The links 26 and 27 are pivotally connected together at their lower and upper ends respectively as indicated at 34. A leaf spring 35 secured to the bracket 31 exerts pressure on the link 26 tending to force it transversely from its normal extended plane, so that when, by means of the cables 18, the lower of the two bars is elevated, the links 26 and 27 will be forced from their normal dead center position, thereby permitting the continued elevation of the said lower bar 22 until, as shown in Fig. 4, this lower bar engages the under side of the next higher bar. During this upward movement of the lower bar of the connected pair, the links 26 and 27 will fold progressively toward each other until they eventually assume the positions in which they are shown in Fig. 4. The spring 35 insures the folding together of the links 26 and 27 in the proper direction. The links 23-24, as previously set forth, are similarly constructed and are adapted to fold together in like manner as the upper bar 21 of the series is elevated.

It will be apparent, therefore, that if the motor 6 is operated in a direction drawing the cables 18 onto the drums 16, the lower bar 22 will be drawn upwardly into engagement with the adjacent bar 21. This bar 21 will then be lifted by the bar 22 into engagement with the next higher bar, and the entire series of bars will in this manner be progressively elevated in a relatively collapsed condition until the entire series lies in a compact mass at the level of or above the platform 1, thereby leaving the entrance area unobstructed. For returning the device to the operative position, the motor 6 is actuated in the opposite direction, thereby progressively lowering the bars into their original positions supported by the links 23-24 and 26-27.

As shown in Fig. 2, the extremities of each of the bars 21 and 22 are provided with T-shaped shoes 36 which are slidably engaged in a correspondingly slotted guide strip 37 secured in vertical position to the wall surface at opposite sides of the door 4. The bars are thus in effect locked to the wall surface and are prevented from swinging away from the latter. Provision is also made for locking the lower bar 22 of the series at or near the floor level. This device, as shown in Fig. 5, consists of a hasp element 38 adjustably secured at 39 in a recess 41 in the floor. This hasp element when elevated, as shown in Fig. 5, lies in proximity to the bar 22, and the latter is apertured to permit the passing therethrough of a padlock 42, which also passes through the hasp 38 and thereby locks the bar 22 at the floor. If required, such locking means may be provided at the front of the bar 22 and at each side thereof. Other means for locking the device in the operative position may be employed without departure from the invention.

The friction clutch 11 provides means for slippage between that part of the shaft 8 directly connected to the motor 6 and the adjoining part which carries the worm 12, so that when the device has moved either to the lowered or operative position or into the retracted or inoperative position, continued operation of the motor 6 will cause no damage to the parts. I prefer, however, to employ means for automatically deenergizing the motor 6 when the bars 21 and 22 have moved into either of the two positions named.

This device consists of a switch 43 mounted in the present instance near the top of the device which is operatively connected through a finger 44 with a cable or belt 45, this cable 45 operating on two suitably supported pulleys 46 and 47. The cable 45 carries two lugs or sleeves 48 and 49 which are arranged for engagement with a lug 51 secured in the present instance to the lower bar 22 of the series, see Fig. 1. When the bar 22 moves into its lowered position and as shown in Fig. 1, the lug 51 engages the sleeve 49, thereby moving the cable 45 on its pulleys in the direction indicated by the arrow at the bottom of the said figure. This effects an actuation of the switch 43, breaking the circuit of the motor 6 and deenergizing the latter. Similarly when the lower bar 22 of the series approaches its elevated position, the lug 51 engages the sleeve 48, thereby causing a reverse movement of the cable 45 reactuating the switch 43 and again deenergizing the motor 6. By reference to Fig. 6, it will be noted that the motor circuit comprises a manually-actuated switch 52 which when thrown to the left from the position in which it is shown and with the switch 43 remaining as shown will close the motor circuit. This position of the switch 43 corresponds to the position in which it is shown in Fig. 1, wherein the bars 21 and 22 are in the operative position. Movement of the switch 52 to the left as described and the subsequent energization of the motor 6 will cause a rotation of the shaft 14 such as to draw in the cables 18 upon the drums 16, thereby elevating the bars 21 and 22. As the bars approach their normal elevated or retracted position, the lug 51 will engage the sleeve 48 on the cable 45, thereby moving the cable in the direction indicated by the arrow in Fig. 6 and actuating the switch 43 to break the motor circuit. Reverse movement of the switch 52 into the position in which it is shown in Fig. 6 will again complete the motor circuit and will effect operation of the motor in the reverse direction, lowering the bars 21 and 22 until such time as the lug 51 engages the sleeve 49, whereupon the switch 43 will be actuated to again break the motor circuit. It will be understood that the worm 12 and worm wheel 13 will not overrun, and will prevent the weight of the bars 21 and 22 under any conditions from turning the shaft 14. Thus there is no requirement for any special means for locking the bars in the retracted position, although such extra locking means may be provided if desired.

In order to conceal the operating parts of the mechanism located on or above the platform 1, I prefer to provide a housing 53 which extends downwardly from the ceiling 5, as shown in Fig. 1, and which as shown in Fig. 2 embraces the platform 1. In the retracted position, the bars 21 and 22 will be elevated above the lower edge of the housing 53, so that the device presents an unobjectionable appearance.

I claim:

1. In a retractable enclosure device for the entrance area of a room interior, the combination with an articulated enclosure structure consisting of a plurality of transverse members shaped to define the normally open sides of said area and means for flexibly connecting said members in series to permit extension and contraction of the said structure as a whole, of means for supporting an end member of said series in an elevated position so that when the structure is extended the other end member lies adjacent to the floor

surface, vertical guides for the extremities of said members positioned at the wall surfaces on opposite sides of said entrance in which said extremities are slidably retained, and means connected 5 to the lower end of said structure for elevating and lowering the structure into and from the contracted position.

2. In a retractible enclosure device for the entrance area of a room interior, the combination 10 with an articulated enclosure structure consisting of a plurality of transverse members shaped to define the normally open sides of said area and means for flexibly connecting said members in series to permit extension and contraction of the 15 said structure as a whole, of means for supporting an end member of said series in an elevated position so that when the structure is extended the other end member lies adjacent to the floor surface, vertical guides for the extremities of said 20 members positioned at the wall surfaces on opposite sides of said entrance in which said extremities are slidably retained, a platform located above said structure and forming a closure for the top of said enclosure, and means including 25 elements supported on said platform for elevating and lowering the structure into and from the contracted position.

3. A retractible enclosure for separating an interior area embracing a doorway from the remainder of the interior, said enclosure comprising 30 a plurality of elongated transversely extending members each shaped to define the normally open sides of said area, means for flexibly connecting said members in vertical series to form an articulated 35 structure capable of extension and contraction as a whole in the vertical direction, means for supporting one end member of said series in an elevated position so that when the structure is extended the other end member lies adjacent to the floor surface, means for securing the ends of 40 said members for vertical movement at the wall surfaces at opposite sides of the doorway respectively, and means connected with the last-named end of said structure for elevating and lowering 45 the structure into and from the contracted position.

4. A retractible enclosure for separating an interior area embracing a doorway from the remainder of the interior, said enclosure comprising 50 a plurality of elongated transversely extending members each shaped to define the normally open sides of said area, means for flexibly connecting said members in vertical series to form an articulated structure capable of extension and 55 contraction as a whole in the vertical direction, means for supporting one end member of said series in an elevated position so that when the structure is extended the other end member lies adjacent to the floor surface, means for securing 60 the ends of said members for vertical movement at the wall surfaces at opposite sides of the doorway respectively, means connected with the last-named end of said structure for elevating and lowering the structure into and from the contracted 65 position, and means for releasably locking the said lower end member at the floor surface.

5. A retractible enclosure for separating an interior area embracing a doorway from the remainder of the interior, said enclosure comprising 70 a plurality of elongated transversely extending members each shaped to define the normally open sides of said area, means for flexibly connecting said members in vertical series to form an articulated structure capable of extension and 75 contraction as a whole in the vertical direction,

means for supporting one end member of said series in an elevated position so that when the structure is extended the other end member lies adjacent to the floor surface, means for securing the ends of said members for vertical movement at the wall surface at opposite sides of the doorway respectively, means for elevating and lowering the structure into and from the contracted position, said last-named means comprising a plurality of cables extending upwardly 5 from the lower ends of the structure, and mechanism mounted within the enclosed area and at the top of said structure for drawing up and paying out said cables.

6. A retractible enclosure for separating an 15 interior area embracing a doorway from the remainder of the interior, said enclosure comprising a plurality of elongated transversely extending members each shaped to define the normally open sides of said area, means for flexibly connecting said members in vertical series to form an articulated structure capable of extension and contraction as a whole in the vertical direction, means for supporting one end member of said series in an elevated position so that when the 20 structure is extended the other end member lies adjacent to the floor surface, means for securing the ends of said members for vertical movement at the wall surfaces at opposite sides of the doorway respectively, means connected with the 25 last-named end of said structure for elevating and lowering the structure into and from the contracted position, said flexible connecting means comprising for each adjacent pair of said members a pair of links respectively pivotally connected to said members and to each other, said 30 links being adapted to fold together upon their pivotal connection when the said adjacent members are drawn together, and resilient means operating on said links when the latter are extended and tending to adjust them toward the folded 35 position.

7. A retractible enclosure for separating an interior area embracing a doorway from the remainder of the interior, said enclosure comprising 45 a plurality of elongated transversely extending members each shaped to define the normally open sides of said area, means for flexibly connecting said members in vertical series to form an articulated structure capable of extension and 50 contraction as a whole in the vertical direction, means for supporting one end member of said series in an elevated position so that when the structure is extended the other end member lies adjacent to the floor surface, means for securing 55 the ends of said members for vertical movement at the wall surfaces at opposite sides of the doorway respectively, a platform depending from the ceiling within the area embraced by said structure and closing the top of the latter, and mechanism mounted on said platform for elevating and lowering the structure into and from the contracted 60 position.

8. A retractible enclosure for separating an interior area embracing a doorway from the remainder of the interior, said enclosure comprising 65 a plurality of elongated transversely extending members each shaped to define the normally open sides of said area, means for flexibly connecting said members in vertical series to form 70 an articulated structure capable of extension and contraction as a whole in the vertical direction, means for supporting one end member of said series in an elevated position so that when the structure is extended the other end member lies 75

adjacent to the floor surface, means for securing the ends of said members for vertical movement at the wall surfaces at opposite sides of the doorway respectively, a motor mounted within the area embraced by said structure and at the top of the latter, a shaft mounted adjacent said motor and operatively connected therewith, a plurality of sheaves carried by said shaft, a cable operatively associated with each sheave and

adapted to be taken up and paid out by the latter, means for connecting said cables to the lower end member of said structure at spaced points longitudinally of the latter, a plurality of guide pulleys for each of said cables, and means for reversely operating said motor to effect extension and contraction of said structure. 5

WILLIAM J. CONDON.
